UNITED STATES PATENT OFFICE.

ROBERT E. FISHER, OF CLEVELAND, OHIO.

INTERNAL-COMBUSTION ENGINE.

Application filed March 31, 1921. Serial No. 457,195.

My invention relates to internal combustion engines, more particularly it relates to poppet valves thereof and to means for controlling the same and to means associated therewith. Among the objects of my invention are the following:—

To provide means for positively opening and closing a poppet valve;

To provide means for insuring a yielding 10 connection between the cam shaft and the poppet valve;

To provide a universal joint connection between the cam and the poppet valve;

To provide other details of improvement 15 tending to increase the efficiency and serviceability of an engine of the above character;

To accomplish the foregoing and other useful ends my invention makes use of 20 means hereinafter more fully set forth and claimed.

Referring more particularly to the drawings:—

Fig. 1 is a plan view of the valves, rocker- 25 lever, rocker-shaft and bracket.

Fig. 2 is an end elevation of the rocker-shaft, rocker-bracket, rocker-lever, and rocker-lever block showing the use of a universal joint in connection with the valve.

Fig. 3 is a section through the cam-follower lever showing its engagement with the cam-shaft of the groove type.

Fig. 4 is a side elevation of the cam-shaft, cam-follower lever, and rocker-lever and operating rod. It will be seen that Fig. 4 is an enlargement from the lower section of Fig. 12, and that Fig. 2 is an enlargement from the upper section of Fig. 13.

Fig. 5 is an end elevation of the cam-shaft—a section being taken through the cam-follower and a section also being taken through the engine frame. This figure also shows a side elevation of the cam-follower lever shaft.

Fig. 6 is a plan view of the cam-follower and valve-rocker lever shaft, and shows the universal joint as well as a section of the engine cylinder.

Fig. 7 is a side elevation of the valve-

rocker lever bolted to the rocker-lever bearing block.

Fig. 8 is a plan view of the cam-follower lever and cam rolls, and also shows in plan the flange type of cam-shaft.

Fig. 9 shows the cam-shaft in end elevation, it also shows the cam-follower lever, cam rolls, cam-follower and valve-rocker lever shaft, valve-rocker lever, and a section of the engine frame and cylinder.

Fig. 10 shows in side elevation the cam-shaft of the taper flanged type. It also shows a section through the taper rolls and cam-follower lever with a spiral spring cushion.

Fig. 11 is a plan view of the engine cylinder showing the valve-rocker levers and bracket.

Fig. 12 shows in side elevation a single cylinder engine with my invention; the groove type of cam-shaft being shown.

Fig. 13 is a section on line 13—13, Fig. 12.

Fig. 14 shows an engine cylinder in plan view using my invention.

Fig. 15 shows in side elevation a single cylinder engine with my invention using 75 the flange type of cam-shaft.

Fig. 16 is a section on line 16—16, Fig. 15.

Fig. 17 is a plan view on section line 17—17, Fig. 20.

Fig. 18 is a section on line 18—18, Fig. 80 20, showing cam and rolls on Fig. 17 more clearly. This cam is a modified form of the cam shown in Fig. 3.

Fig. 19 shows in side elevation a single cylinder engine with my invention, making 85 use of the groove type of cam.

Fig. 20 is a section on line 20—20, Fig. 19.

Referring more in detail to the drawings, it will be seen that I provide an engine with poppet valves positively operated both to 90 open and close.

Referring to Fig. 16, the valve is shown horizontally disposed, the stem of the valve projecting toward the left and terminating in a socket, 33. Associated with this socket, 95 33, there is a spring, 48, mounted on the upper end of the rocker-lever shaft, 44. Said spring, 48, is rigidly secured with re-

spect to the shaft, 44. The shaft, 44, on its lower end is provided with an inwardly extending arm, 43, on the end of which is secured the cam-shaft rolls, 22, mounted on 5 the small shaft, 23.

Referring to Fig. 15, it will be seen that the cam-shaft 42 is provided with a pair of flange type cams both of which are shown engaging the cam rolls 22. This shaft, 42, 10 is pivoted in the engine frame and insured against lateral play in any suitable manner as, for example, by the provision of the flange, 55, on the left extremity, and the timing gear, 54. As shown, the gear, 54, 15 meshes with the timing gear, 53, which is mounted on the crank-shaft 52. Obviously, therefore, the rotation of the crank-shaft causes a rotation of the cam-shaft, 42. The rotation of this cam-shaft causes the rotation 20 of the cams there-on and therefore causes the oscillation of the follower-lever arm, 43, about a vertical axis through the center of the rocker-lever shaft, 44. This, of course, causes a corresponding reciprocating movement of the shaft, 44, with the corresponding oscillatory movement of the spring, 48, previously referred to.

Referring to Fig. 15, the spring, 48, is 30 provided with a socket on its right-hand terminal. This is more clearly shown by referring to Fig. 16. It was previously pointed out that there is also a socket on the end of the stem of the valve, 51, now, between these two sockets there is a connecting 35 link consisting of a pair of balls one in each of said sockets, said balls being rigidly connected through the medium of an interconnecting member, 32. These sockets together with these balls so connected form a 40 universal joint between the shaft, 44, and the valve, 51. The object in this arrangement is to insure smoother operation of the valve, 51, and to eliminate unnecessary strains due to the rotation of the spring, 48, 45 about an axis through the center of the shaft 44.

With respect to the spring, 48, it will be 50 seen that by providing such a spring member between the valve, 51, and the shaft, 44, I insure against any harmful results occurring to the mechanism as a result of the valve, 51, reaching its seat before the cam at the lower end of the shaft, 44, has reached the limit of its stroke. By providing a 55 yielding spring such as the spring, 48, I prevent the connecting link between the shaft, 44, and the valve, 51, being bent. In this connection, I may say that I have another safety arrangement which will prevent the bending of the link, 48, in the 60 event that it is not made flexible. In the event that the valve, 51, reaches its seat before the cam completes the limit of its stroke, if the arm, 48, is rigid, the pressure 65 of the cam and the cam-shaft, 42, will re-

sult in forcing the rolls, 22, outwardly with respect to the cam, which, referring to Figs. 15 and 16, will be downwardly, thereby, causing the shaft, 44, to be depressed or slid downwardly, causing a compression of the 70 spring, 27, and thereby insuring against undue strain on the valve or any of the associate parts. I wish to point out further that the spring, 27, also serves to maintain the rolls, 22, in close working engagement with the cam on the cam-shaft, in other words, the spring, 27, serves a double purpose.

Referring to Fig. 14, for the purpose of the description, we may assume that the valve on the right-hand side is on the intake 80 side, and, inasmuch as Fig. 16 is a section through this valve, the valve, 51, may be considered as the intake valve.

Although I have shown the invention in Fig. 15 in connection with flange cams, the 85 groove type of cams such as shown in Figs. 17, 18, 12, 19, 20, and 3 may be used.

Referring more particularly to Figs. 20 and 19, it will be seen that I show my invention in these two figures in connection with an L head type of cylinder. It will be seen also that the valve is shown in a slanting position. It will also be seen that the valve is controlled through the medium of a groove type of cam but it will be understood that either of the other types of cams may be substituted. Regardless of which type of cam is used, it will be seen that the roll-shaft, 23, Fig. 16, corresponds to the pin or roll-shaft, 59, in Fig. 20, and it will 100 also be seen that the follower-lever, 43, in Fig. 16, corresponds to the follower-lever on which the pin, 59, is secured in Fig. 20. In both Figs. 16 and 20 the follower-lever, 43, is securely mounted on one end of a shaft 105 which shaft in Fig. 16 is the shaft, 44, and in Fig. 20 is the shaft, 66.

In Fig. 16 the valve rocker-lever, 48, is mounted on the opposite end of the shaft, 44, to which the universal joint is attached. 110 However, in Fig. 20 the follower-lever is provided with an extension, 60, to which the universal joint is directly attached without the interposition of a flexible arm such as the arm, 48, Fig. 16. However, in both 115 Figures 16 and 20, the spring, 27, is provided to maintain the cam rollers against the cam and to act as a safety device between the cam-shaft and the valve as previously explained.

Referring more in detail to the operation of the means shown in Fig. 20, it will be seen that the rotation of the cam-shaft, 64, causes the oscillation of the arm, 60, about an axis and coincident with the longitudinal 125 axis of the shaft, 66. This oscillation causes a corresponding operation of the poppet valve, 68, through the medium of the universal joint, 32. It will be seen from what has already been said that in the event of the 130

valve, 68, reaching its seat before the cam reaches the limit of its stroke, that the rollers, 61 and 63, will be forced out toward the left, Fig. 20, causing a compression of the 5 spring, 27, with the consequent sliding of shaft, 66, in its longitudinal bearing which is shown in section.

Referring more in detail to the construction of the cam rollers, 61 and 63, it will be 10 seen by referring to Fig. 18, that the roller, 61, engages the upper side of the cam groove whereas the small roll, 63, engages the lower side of the cam groove.

Referring to Figs. 11, 12, and 13, it will be 15 seen that in these drawings I show the application of my invention using the groove type of cam control to an over-head mounted vertical valve. It will be seen that between the follower-arm, 24, and the universal joint, 20 32, I provide a lever-rocker arm, 35, and a second universal joint terminating in the socket, 31, on either end, the balls in which are connected by the rod, 34.

It will be understood from what has already 25 been said that the oscillation of the arm, 24, as a result of the rotation of the cam-shaft, will cause a reciprocal up and down motion of the shaft, 34, which will cause the lever, 35, to rock about the shaft, 37, see Fig. 12, which in turn will cause the 30 operation of the valve, 40. Therefore, the operation of the engine with the variation shown in Figs. 11, 12, and 13, agrees with the operation of the means shown in Figs. 35 19 and 20 except for the interposition of the links, 34 and 35.

In Figs. 2, 4, 5, and 3, I show the application to the mechanism described in connection with Figs. 11, 12, and 13 of the type of 40 cam arrangement shown in Fig. 3. In this type of groove cam, the upper surface of the groove, Fig. 3, is shown engaging the cam roll, 22, on the shaft or pin, 23, whereas the lower surface of the groove is shown engaging 45 the roll on a second similar roll on a second similar pin on the follower-lever, 24.

Figs. 6, 7, 8, 9 and 10 are enlarged details of the cam arrangement shown in Fig. 15.

50 Referring to Figs. 2 and 15, it is noted that the rocker-levers, 35 and 48, may be made of spring steel. By making these members flexible, a positive closing of the valves is insured. Further, safety is insured 55 against undue strain as previously pointed out.

Referring to Fig. 3, it will be noted that the sides of the cam are sloped and the engaging element,—see element 22,—is sloped to prevent friction and to maintain a proper ratio between all of the contacting sections 60 of the surface.

Referring to Figs. 4 and 5, it will be noted that the lever, 24, is fastened to the shaft, 65 25, in any suitable manner as for example

by the use of a tapered pin 26. It will be understood, of course, that the shaft, 25, oscillates in the bearing, 30, which oscillating movement is produced by the cam, 21. The lever-shaft and rolls are free to move end- 70 wise in the bearing, 30, in the event of excessive strain and subject to the control of the spring, 27. The spring, 27, further maintains constant working engagement between the rolls, 22, and the cam regardless 75 of wear. The provision of the lengthwise movement of the shaft, 25, in the bearing, 30, serves to cushion the closing of the valve, 40, and also prevents damage to the parts in case the stem of the valve,—valve 40 for example,—should stick.

In an internal combustion engine using poppet valves, it has been found heretofore that with the increase of speed of the engine beyond a certain point the efficiency of the 85 engine begins to drop off as a result of the poppet valve having to depend upon a spring to close the valve. With my invention, I insure the positive action of the valve in both 90 directions and free the engine from the limitation in efficiency due to the lack of positive action of the valve in both directions. Furthermore, with my invention I produce an engine which is much more silent than engines in which the poppet valves are closed 95 by spring action. Furthermore with the old type of construction a clearance is provided between the valve stem and the lifter to allow for the expansion in the valve and on account of this clearance, lost motion results and also a click follows every time that 100 the single acting cam starts to lift the valve. In my type of construction, I eliminate the use of a spiral type valve stem spring commonly used for closing the valve and I 105 eliminate the clearance, all of which produces an engine that runs very quietly.

With reference to the cams shown in the drawings, I wish to refer to the section on the cam-shaft as the cam and the rolls as 110 the engaging element.

I wish to further point out the importance of the cap, 28, Fig. 20. This cap may be used for varying the tension of the spring 115 27. It will be seen that this spring effects the opening of the valve, 68. In the case of the exhaust valve it will be seen that as the pressure of the gas in the cylinder varies the pressure necessary to lift the valve varies. It will be seen that with a given tension on 120 the spring, 27, the cam may not be able to lift the valve immediately—instead the cam will begin to move the lever, 60, away from the cam against the tension of the spring, 27. This will, of course, increase the tension in 125 the spring, 27, until the pressure of the spring is great enough to overcome the gas pressure on the head of the exhaust valve at which point the exhaust valve will begin to open. It will be observed therefore that by 130

regulating the tension of the spring, 27, the timing of the valve may therefore be regulated. In other words, the opening act will take place later with a light tension on the spring, 27, than with a heavy tension. It will also be seen that the sloping surfaces of the cam and cam engaging element is important in this connection. Therefore it will be seen that I have provided an engine in which 10 the timing may be regulated while the engine is running, by regulating the cap, 28, and therethrough regulating the tension in the spring, 27.

What I claim as my invention is:—

15 1. In an internal combustion engine, a crank-shaft, a cam operated by said shaft, a poppet valve, a cam engaging element, the valve connected with said element by a link whereby the valve may be both opened and 20 closed by said cam, and a spring for maintaining the cam engaging element pressed against the cam, and whereby in the event the valve does not respond, the cam may 25 force said element out from the cam axis of rotation and avoid injury to any of the parts.

2. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after 30 the valve strikes its seat, will flex the link and prevent injury to any of the parts, and a spring for maintaining the cam engaging element pressed against the cam, and whereby in the event the valve does not respond, the cam may force said element out from the cam axis of rotation and avoid injury to 35 any of the parts.

3. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed 40 against the cam, and whereby in the event the valve does not respond, the cam may force said element out from the cam axis of rotation and avoid injury to any of the parts, said link including a universal joint.

45 4. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and prevent injury to any of the parts, and a 50 spring for maintaining the cam engaging

element pressed against the cam, and whereby in the event the valve does not respond, the cam may force said element out from the cam axis of rotation and avoid injury to any of the parts, said link includ- 70

5. In an internal combustion engine, a crank-shaft, a cam operated by said shaft, a poppet valve, a cam engaging element, the valve connected with said element by a link 75 whereby the valve may be both opened and closed by said cam, and a spring for maintaining the cam engaging element pressed against the cam, and whereby in the event the valve does not respond, the cam may 80 force said element out from the cam axis of rotation and avoid injury to any of the parts, said link having a shaft at right angles to the valve stem, an arm for said shaft projecting off therefrom and to the outer 85 end of which arm the valve stem is attached.

6. In an internal combustion engine, a crank-shaft, a cam operated by said shaft, a poppet valve, a cam engaging element, the valve connected with said element by a link 90 whereby the valve may be both opened and closed by said cam, the link being flexible whereby the continued operation of the said cam engaging element by the cam after the valve strikes its seat, will flex the link and prevent injury to any of the parts, and a spring for maintaining the cam engaging element pressed against the cam, and whereby in the event the valve does not respond, the cam may force said element out from the cam axis of rotation and avoid injury to 95 any of the parts, said link having a shaft at right angles to the valve stem, an arm for said shaft projecting off therefrom and to the outer end of which arm the valve stem is attached.

7. In an internal combustion engine, a crank-shaft, a cam operated by said shaft, a poppet valve, a cam engaging element, the valve connected with said element by a link 100 whereby the valve may be both opened and closed by said cam, and a spring for maintaining the cam engaging element pressed against the cam, said link having a shaft at 105 right angles to the valve stem, an arm for said shaft projecting off therefrom and to the outer end of which arm the valve stem is attached, said link also having a second arm projecting off from said shaft, the outer 110 end of which arm terminates in the cam engaging element.

8. In an internal combustion engine, a crank-shaft, a cam operated by said shaft, a poppet valve, a cam engaging element, the valve connected with said element by a link 115 whereby the valve may be both opened and closed by said cam, the link being flexible whereby the continued operation of the said cam engaging element by the cam after 120 the valve strikes its seat, will flex the link and prevent injury to any of the parts, and a 125 spring for maintaining the cam engaging element by the cam after 130

- the valve strikes its seat, will flex the link and prevent injury to any of the parts, and a spring for maintaining the cam engaging element pressed against the cam, said link having a shaft at right angles to the valve stem, an arm for said shaft projecting off therefrom and to the outer end of which arm the valve stem is attached, said link also having a second arm projecting off from said shaft, the outer end of which arm terminates in the cam engaging element.
9. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed against the cam, and whereby in the event the valve does not respond, the cam may force said element out from the cam axis of rotation and avoid injury to any of the parts, said link having a shaft at right angles to the valve stem, an arm for said shaft projecting off therefrom and to the outer end of which arm the valve stem is attached, said link also having a second arm projecting off from said shaft, the outer end of which arm terminates in the cam engaging element.
10. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and prevent injury to any of the parts, and a spring for maintaining the cam engaging element pressed against the cam, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam.
11. In an internal combustion engine, a crank-shaft, a cam operated by said shaft, a poppet valve, a cam engaging element, the valve connected with said element by a link whereby the valve may be both opened and closed by said cam, a spring pressing the element against the cam and the engaging surfaces of the cam and of the cam engaging element sloping towards the axis of rotation of the cam whereby in the event of excessive strain along the link, the cam engaging element compresses the said spring thereby relieving the strain between the element and the cam and thereby preventing injury to the parts.
12. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed against the cam, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam.
13. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and prevent injury to any of the parts, and a spring for maintaining the cam engaging element pressed against the cam, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam.
14. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed against the cam, and whereby in the event the valve does not respond, the cam may force said element out from the cam axis of rotation and avoid injury to any of the parts, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam.
15. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and

- prevent injury to any of the parts, and a spring for maintaining the cam engaging element pressed against the cam, and whereby in the event the valve does not respond, the cam may force said element out from the cam axis of rotation and avoid injury to any of the parts, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam, and to the outer end of which arm the valve stem is attached, said shaft journaled whereby the link oscillates about the longitudinal axis of the shaft responsive to the action of the cam.
16. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed against the cam, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam, said link operating to open the valve upon its oscillation in one direction and operating to close the valve upon its oscillation in the opposite direction.
17. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and prevent injury to any of the parts, and a spring for maintaining the cam engaging element pressed against the cam, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam, said link operating to open the valve upon its oscillation in one direction and operating to close the valve upon its oscillation in the opposite direction.
18. In an internal combustion engine, a crank-shaft, a cam operated by said shaft, a poppet valve, a cam engaging element, the valve connected with said element by a link whereby the valve may be both opened and closed by said cam, and a spring for maintaining the cam engaging element pressed against the cam, and whereby in the event the valve does not respond, the cam may force said element out from the cam axis of rotation and avoid injury to any of the parts, said link having a shaft, at right angles to the valve stem, an arm for said shaft projecting off therefrom and to the outer end of which arm the valve stem is attached, said shaft journaled whereby the link oscillates about the longitudinal axis of the shaft responsive to the action of the cam, said link operating to open the valve upon its oscillation in one direction and operating to close the valve upon its oscillation in the opposite direction.
19. In an internal combustion engine, a crank-shaft, a cam operated by said shaft, a poppet valve, a cam engaging element, the valve connected with said element by a link whereby the valve may be both opened and closed by said cam, the link being flexible whereby the continued operation of the said cam engaging element by the cam after the valve strikes its seat, will flex the link and prevent injury to any of the parts, and a spring for maintaining the cam engaging element pressed against the cam, and whereby in the event the valve does not respond, the cam may force said element out from the cam axis of rotation and avoid injury to any of the parts, said link having a shaft at right angles to the valve stem, an arm for said shaft projecting off therefrom and to the outer end of which arm the valve stem is attached, said shaft journaled whereby the link oscillates about the longitudinal axis of the shaft responsive to the action of the cam, said link operating to open the valve upon its oscillation in one direction and operating to close the valve upon its oscillation in the opposite direction.
20. In an internal combustion engine, a crank shaft, a cam rotated by said shaft, a poppet valve, an element engaging said cam and operated thereby, the valve connected with said element whereby the valve may be operated by said cam, the cam surface engaged by said element sloping with respect to the axis of rotation of the cam, and a spring for maintaining the cam engaging element pressed against the cam, and means to vary the tension of said spring.
21. In an internal combustion engine, a crank shaft, a cam rotated by said shaft, a poppet valve, an element engaging said cam and operated thereby, the valve connected with said element whereby the valve may be operated by said cam, the cam surface engaged by said element sloping with respect to the axis of rotation of the cam, the engaging element being conical, the surface of the cone sloping with respect to the axis of rotation of the cam, and a spring for maintaining the cam engaging element pressed against the cam, and means to vary the tension of said spring.
22. In an internal combustion engine, a crank shaft, a cam rotated by said shaft,

5 poppet valve, an element engaging said cam and operated thereby, the valve connected with said element whereby the valve may be operated by said cam, the cam surface engaged by said element sloping with respect to the axis of rotation of the cam, the engaging element being conical, the surface of the cone sloping with respect to the axis of rotation of the cam, the surface of the cone engaged 10 by said cam pivoted to rotate, and a spring for maintaining the cam engaging element pressed against the cam, and means to vary the tension of said spring.

15 23. In an internal combustion engine, a crank shaft, a cam rotated by said shaft, a poppet valve, an element engaging said cam and operated thereby, the valve connected with said element whereby the valve may be operated by said cam, the cam surface engaged by said element sloping with respect to the axis of rotation of the cam, the connecting means between the valve and the said element consisting of a flexible link, whereby the cam may continue to move said element after the valve strikes its seat without injuring said valve, and a spring for maintaining the cam engaging element pressed against the cam, and means to vary the tension of said spring.

20 24. In an internal combustion engine, a crank shaft, a cam rotated by said shaft, a poppet valve, an element engaging said cam and operated thereby, the valve connected with said element whereby the valve may be operated by said cam, the cam surface engaged by said element sloping with respect to the axis of rotation of the cam, and a spring for maintaining the cam engaging element pressed against the cam, and means to vary the tension of said spring while the engine is running.

25 25. In an internal combustion engine, a valve and an operating cam, interconnecting mechanism between the cam and the valve for positively operating the valve from said cam both to open and close the valve, a yielding connection between the cam and the valve whereby the valve may be held in any position while the cam continues to operate without the force of the cam damaging the valve.

30 26. In an internal combustion engine, a valve and an operating cam, interconnecting mechanism between the cam and the valve for positively operating the valve from said cam both to open and close the valve, a yielding connection between the cam and the valve whereby the valve may be held in any position while the cam continues to operate without the force of the cam damaging the valve,

and adjusting means for regulating the yielding connection to regulate the amount of force that the cam can deliver to the valve.

35 27. In an internal combustion engine, a valve and an operating cam, interconnecting mechanism between the cam and the valve for positively operating the valve from said cam both to open and close the valve, a yielding connection between the cam and the valve whereby the valve may be held in any position while the cam continues to operate without the force of the cam damaging the valve, and adjusting means for regulating the yielding connection to regulate the amount of force that the cam can deliver to the valve whereby the timing of the valve may be varied as the pressure of the gas in the cylinder varies.

40 28. In an engine a cam, a valve, a cam engaging element, connecting means between said element and said valve, said valve and element so constructed that when the valve is free to move, the said element is restricted to one path of motion but when the valve is impeded at any point in its cycle of movement, said element is forced to follow a different path.

45 29. In an engine a cam, a valve, a cam engaging element, connecting means between said element and said valve, said valve and element so constructed that when the valve is free to move, the said element is restricted to one path of motion but when the valve is impeded at any point in its cycle of movement, said element is forced to follow a different path, a spring for retaining said element in said first path as long as the impeding force of the valve is below a given magnitude but responsive to said impeding force when it reaches the given magnitude to permit the element to move against the spring tension.

50 30. In an internal combustion engine, a valve and an operating cam, interconnecting mechanism between the cam and the valve for positively operating the valve from said cam both to open and close the valve, a yielding connection between the cam and the valve whereby the valve may be held in any position while the cam continues to operate without the force of the cam damaging the valve, said construction involving a grooved cam in which said element operates, and a sloping side for said groove and for said element whereby said element may slide on said side in a direction having a component across the groove.

55 In witness whereof, I have hereunto signed my name this 28 day of March, 1921.

ROBERT F. FISHER.
